UNITED STATES PATENT OFFICE.

WARREN H. MILLER, OF INTERLAKEN, NEW JERSEY.

DESIGN FOR A TENT.

45,016.

Specification for Design.

Patented Dec. 9, 1913.

Application filed July 10, 1913. Serial No. 778,390. Term of patent 7 years.

To all whom it may concern:

Be it known that I, WARREN H. MILLER, a citizen of the United States, residing at Interlaken, State of New Jersey, have invented a new, original, and ornamental Design for Tents, of which the following is a specification, reference being had to the accompanying drawing, forming part thereof.

The figure is a perspective view of a tent showing my new design.

I claim:

The ornamental design for a tent, as shown.

WARREN H. MILLER.

Witnesses:

HERBERT G. OGDEN,
M. M. RIEMANN.
